SIDE BY SIDE DRUM MIXING MACHINE

Emil L. Tranaas, Milwaukee, Wis., assignor to
Koehring Company, Milwaukee, Wis., a corporation

Application December 1, 1930, Serial No. 499,853

6 Claims. (Cl. 83—73)

The present invention appertains to improvements in machines known as concrete pavers, which generally comprise today as employed in commercial practice, a concrete mixer including a mixing drum supported upon a portable base comprising suitable traction devices and equipped with a loading skip adapted to receive dry aggregates of the concrete and then to be elevated so as to discharge these aggregates into the mixing drum for admixture with water. The paver includes also a distributing mechanism usually in the form of a bucket traversing a boom. While the invention is shown as applied to such a type of paving or distributing machine, it is to be understood that the newly invented instrumentalities hereinafter presented may be readily employed in connection with other distributing mechanism than the boom and bucket type mentioned.

Now in the operation of paving machines wherein a single drum is employed, it is required by specifications or regulations of different states that the mixing time in the mixing drum shall be at least sixty seconds and sometimes a greater time is required. This requirement is necessary in order to insure the integrity of the final mix when discharged from the drum.

The efficiency of machines of this type is determined as to speed of the mixing operation by the time that the aggregates are maintained in the mixing drum. The loading means which is the skip, is capable of working much faster than the time required for the drum mixing action, and furthermore, the discharge and distributing instrumentalities associated with the drum, are capable of working much faster than the mixing time ordinarily allowed, as will be apparent to those versed in the art.

The intention of this invention, therefore, has been to raise the efficiency of the machine by increasing its mixing capacity, to which end I employ a duplex drum arrangement in which the drums for performing the mixing are arranged side by side. I furthermore employ a novel form of loading skip of a construction adapted to feed or load a batch into one of the drums, and while the mixing operation is being performed therein, this skip is adapted to return to its receiving position, receive, and then discharge another batch into the second.

While the concrete is being mixed in the second drum, the skip will return to its receiving position again, receive another charge of aggregates, and in due course, be ready to supply this fresh charge of aggregates to the first drum referred to

which has been continuously mixing while the operation of loading the second drum is being performed. In other words, from the foregoing, it will be apparent that by putting two drums into action in my paver, a more continuous supplying and discharging of the aggregates is permitted because of the ability to work the loading skip faster and the capability of working the discharging instrumentalities at more frequent intervals, and the further capability of the distributor working to do two times the work that it would ordinarily perform.

There are employed in the carrying out of my invention, additionally, certain automatic devices that control the alternate charging of the mixing drums from the skip, the alternate actuation of the water valves controlling the admission of water to the drums, the alternate actuation of the discharge devices for the respective drums, and certain parts establishing interlocking controls between the said parts in order that my machine may work at high efficiency along the lines which I have described above.

A full understanding of the present invention will be had upon reference to the accompanying drawings, in which:

Figure 1 is a side elevation of a paving machine embodying the invention.

Figure 2 is a top plan view of the main features of the machine showing particularly the side by side arrangement of the drums, parts being omitted.

Figure 3 is a rear view of the machine looking into the charging skip or device, parts being omitted.

Figure 4 is a view of the machine looking from the front end, or opposite from the view of Figure 3, and omitting the boom and bucket distributing instrumentalities so that the parts that are desired to be illustrated may be more clearly seen.

Figure 5 is a diagrammatic showing of the mixing cycles of the machine.

Figure 6 is a detail view of gearing and pawl and ratchet mechanism employed for shifting the deflector in the loading skip from a position in which it will cause the skip to supply the aggregates to one drum, to a position in which the skip will supply the aggregates to the second drum.

Figure 7 is a view showing more clearly the ratchet device illustrated in Figure 6.

There will first be described, the general instrumentalities employed in my machine, after which there will be set forth the operation of

these instrumentalities in their regular order so as to supply a full understanding of the invention.

Now referring to Figures 1 and 2 particularly, A denotes traction devices illustrated diagrammatically, which carry the base B of the paver frame, the superstructure frame of which is designated C. Supported upon the base of the machine, in any well known manner, and preferably by means of antifriction rollers, are the drums 16 and 17 arranged side by side, in aligned disposition. At the rear end of the machine where it will be supplied with the dry concrete aggregates, is the loading skip 1 which has the usual supporting arms pivotally connecting it with an axis 20 about which the skip is adapted to be raised to discharge its contents into the charging openings of the respective drums 16 and 17. There is mounted in the discharge portion of the skip 1 a deflector 24 adapted to swing about a pivotal point 24a so that in one of its positions, it will cause the aggregates in the skip to discharge through the discharge spout 1b into the drum 17, and this position is illustrated in full lines in Figure 2. When the deflector 24 is moved to the other position of the dotted lines of Figure 2, the contents of the skip may be discharged through the spout 1c into the mixing drum 16.

30 The mixing drums are preferably of the type in which annular gear rings 16a and 17a for the respective drums 16 and 17 are utilized. A drive pinion 40, see Figure 3, meshes with a gear ring 16a of the drum 16 and is operated from an engine shaft to turn the drum. Where two gear rings are employed, two driving pinions may be utilized obviously. The gear rings of the drums 16 and 17 have their teeth in mesh so that the drive to the drum 16 may be transmitted to the drum 17. However, if desired, separate drive pinions for the two drums may be utilized and operated from the engine shaft by suitable gearing.

The drums 16 and 17 are side by side and a water tank 25 is provided to supply water to the drum 16 while a tank 26 correspondingly supplies water to the drum 17. I contemplate utilizing any well known form of three-way valve 25a to control the passing of water from the tank 25 to the drum 16 and to control the admission of water to the tank for replenishment purposes, said water coming from a main line supplying the customary way. Such valve mechanism is known and illustrated by Lichtenberg Letters Patent No. 1,525,100 issued February 3rd, 1925. A similar valve 26a to the valve 25a is provided for the tank 26 and the drum 17, and to operate the valves aforesaid, there is provided a trip arm 8 which is carried by the axis member 24a of the deflector 24 and movable from a position to actuate the valve 25a to a position to actuate the valve 26a by adjustments caused by the movement of the deflector 24 from one of its positions to the other.

The trip arm 8 is adapted to strike the upper arm 2a of the T-shaped lever 2 carried on the framework of the mixing machine to thereby actuate through a link 25b the valve arm of the valve arm 25a on the upward movement of the skip, thereby to open the supply of water from the tank 25 to the drum 16. On the downward movement of the skip, the trip arm 8 will hit a second arm 2b of the lever 2 and close the water valve 25a so as to replenish the water in the tank 25. This identical arrangement of trip means 2, 2a, 2b and a link 26b is provided for the

valve 26a of the tank 26, see Figure 2, and it will be obvious that dependent upon the position of the deflector 24, a certain one of the levers 2 will be actuated so as to operate the water valve that is associated with the mixing drum that is being charged by the skip 1.

Now it is obvious that it is desired that the skip 1 supply a charge of aggregates to the drums 16 and 17 alternately, and therefore, it is simply necessary that upon each operation of lowering the skip, the deflector 24 shall be shifted from the position wherein it will supply aggregates say to the drum 16, to a position in which it will next supply the aggregates to the drum 17 and so I utilize the up and down movement of the skip 1 for alternately shifting the deflector 24 from one position to the other for the purpose described.

This means employed is very simple and consists of a stationary shaft 20, a stationary gear 19 carried thereby, a pinion 18 actuated by the gear 19 and mounted on a suitable shaft 18a carried by skip supporting arms. The shaft 18a carries, affixed thereto, a pawl carrier 21 of ratchet mechanism including the ratchet wheel 21a, the pawls of the pawl carrier being designated 21b. The pawl carrier 21 and the pinion or gear 18 are a unit and are loose upon the shaft 18a, said shaft 18a carrying fixed thereto the ratchet wheel 21a, previously mentioned. Also fixed on the shaft 18a is the deflector actuating arm 23 connected by a link 23a to the lever 23b pivoted on the frame of the machine, said lever 23b having a link 23c connecting it pivotally with a crank arm 23d affixed to the axis member or shaft 24a that forms the pivot of the deflector 24.

As the skip 1 is raised, the pinion 18 is rotated and also the pawl carrier 21 in a contra-clockwise direction. At such time, the pawls 21b freely escape over the ratchet teeth of the ratchet wheel 21a. On the down movement of the skip 1, however, the gear 18 rotates in a clockwise direction, turns the pawl carrier 21 likewise, and the pawls 21b turn the ratchet wheel 21a and rotate the arm 23 180 degrees thereby actuating the deflector 24 to shift it about 90 degrees from one extreme of movement to the other, so that the trip arm 8 previously referred to is correspondingly adjusted by such action.

This brings us to the discharge devices for the drums and to the batchmeters which are utilized, these parts as separate units, being well known in this art, and being of suitable construction. Typical of power discharge devices such as may be used, are the constructions in the Robb Letters Patent No. 1,660,301, issued February 21st, 1928, Webb Letters Patent No. 1,628,378, issued May 10th, 1927, and Menningen Letters Patent No. 1,648,144, issued November 8th, 1927. Thus there is a batchmeter 14 for the drum 16, a batchmeter 13 for the drum 17, and a power discharge 5 which is common to the two discharge chutes of the mixers 16 and 17, said chutes being designated 6 and 7.

Now there is employed as a part of the power discharge, as usual, an actuating member or bar 5a. Instrumentalities are provided to alternately interlock this bar to operate the discharge chute 6 at one adjustment, and thereafter, the discharge chute 7 at a different adjustment of parts. The parts controlling these operations will now be set forth.

The actuating member or bar 5a is pivotally connected at 5b to a sleeve-like coupler bar 15 provided at its ends with pawls or arms 15a and 15b. The arms or pawls 15a and 15b are angularly dis-

posed, relative to each other, so that when the arm 15a is out of engagement with the actuating hook bar 8a for the chute 6, the member 15b will be in engagement with the corresponding bar 7a for the chute 7.

The coupler bar 15 is rotative for adjustment relatively to the parts 15a and 15b by a link 12 connecting a central arm 15c of the coupler bar with the arm 12a carried by a shaft 12b on the framework C. The shaft 12b carries also arms 10a connected with an actuating rod 10 and arm 29a connected with an actuating rod 29, the right ends of which rods as seen in Figure 1, are guided by a guide bracket 41. On the right hand ends of the rods 10 and 29 are carried rollers or similar abutment parts 9 and 28, with which the trip arm 18 carried by the skip is adapted to alternately engage, depending upon its position of adjustment. In the above manner, by reason of actuation of the parts 10 and 29 from the skip, the coupler bar 15 may be properly adjusted to be pre-set to actuate a particular one of the chutes 6 and 7 depending upon the cooperation of the parts 15a and 15b. The shaft 12b also has links 11 and 11a connected with the arms 10a and 29a so that the actuation of the rods 10 and 29 may actuate the usual parts of the batchmeters 13 and 14 whereby to set each batchmeter into operation when its arm is actuated for such purpose, after the well known manner. The batchmeters 13 and 14 may be of the types shown by Lichtenberg Letters Patent No. 1,321,460, issued November 11th, 1919 and Winkler et al. Patent No. 1,282,558, issued October 22nd, 1918. The batchmeters are, of course, set therefore incident to actuation of the parts 10 and 29 from the skip 1.

The batchmeters 13 and 14 control the power discharge mechanism 5 in the well known manner, as presented in the Robb, Webb and Menning patents herein set forth, so as to set the power discharge into operation at a predetermined time, namely when the batchmeter-controlled-period of mixing has terminated thus causing the power discharge to operate and move the actuating bar or member 5a, and thus turn the particular selected one of the discharge chutes 6 and 7 to its proper position of adjustment. The connecting means between the batchmeter 13 and the power discharge 5 is a link 13a and the corresponding connecting means between the batchmeter 14 and power discharge 5 is the link 14a, see Figures 1 and 4. Certain of these connections are rather diagrammatically illustrated in the drawings because the constructions of power discharge devices and batchmeters are well known to those versed in the art. In this connection, reference may be made to the type of power discharge shown by the Bathrick Patent No. 898,171, issued September 8th, 1908, and Shafer Patent No. 1,415,411, issued May 9th, 1922.

When the power discharge unit 5 is operated, an arm 31a of the mechanism, see Figure 1, actuates a link 31 connected by a bell crank with a rod 30 that leads to and is connected with the lower end of a lever 4, the upper end of which is beneath the crank 3 which carries a roller for contact with said lever 4.

At the time of contact between the parts 3 and 4, the lever 4 will be rocked to the left at its upper end, see Figure 1. This happens by reason of the fact that the arm 3 is rigid with the left pivot bracket of the skip 1, and therefore tilts downwardly when the skip is raised thus communicating to the lever 4 a rocking movement that operates the parts 30, 31 and 31a to set the

power discharge into action under the control of the skip, at certain predetermined times. This is for the purpose of restoring to non-discharging positions that one of the discharge chutes 6 or 7 which happens at the time to be in discharging position. The power discharge mechanism 5 therefore is operable both from the batchmeters and from the skip, to be operated by the skip to effect a non-discharging adjustment of a chute, and to be operated from the batchmeters to place one or the other of the chutes in discharging position for emptying of a particular mixing drum, as may be required. When in the operation of the machine a discharge chute 6, or 7, as the case may be, is moved through operation initiated by the skip 1 from a discharging position to a non-discharging position, the other chute is not affected.

The preferred operation of my twin mixer, as described, involves maintaining the aggregates being mixed in each drum for a period of sixty seconds according to the diagram of the mixing cycle given in the drawings, but this period may be fixed at whatever time desired, according to the regulations under which the concrete is being made.

When the sixty second mixing period is employed for each drum, the discharge chute for the drum 17 will be operated at the completion of the sixty second mixing cycle in said drum. 34.5 seconds after the discharge of the drum 17, the chute 7 of the drum 16 will be turned over to discharging position and discharge the contents of that drum. In more simple words, there is an elapsed time of 34.5 seconds between the discharges of the batches from the two drums. The diagram of Figure 5 shows that the mixing operations of the two drums overlap for a few seconds, the overlapping period being approximately 25.5 seconds.

Now a full cycle of the operation of my machine will be described to convey a final understanding of the advantages and special operations. Let us assume that the engine or motor of the machine has been started and the skip hoist clutch 42 has been thrown in by the manual operation of the lever 43 which lever 43 is connected to the power discharge 5 by a rod 32, see Figure 1. The operator makes certain that the swing chute 6 is in its discharge position and that the chute 7 is in its mixing position. The skip 1 has been loaded from trucks or batch boxes with the necessary aggregates to be mixed for one batch in one drum. The engagement of the skip hoist clutch first manually by the lever 43 causes the skip 1 to raise and carry its contents into one of the mixing drums.

As the skip approaches its upper limit of movement, the roller 3 strikes the cam member or lever 4 and trips the power discharge unit 5 which thereby moves the chute 6 into its non-discharging position. The trip lever 8 on the skip ultimately hits the roller 9 of the rod 10 pushing the rod so as to set the batchmeter 14 through the rod 11, also pushing the rod 12 turning the coupler bar 15 into engagement with the swing chute operating bar 7a for the chute 7, and out of engagement with the corresponding bar for the discharge chute 6. The skip, then through well known clutch knock-out mechanism customarily provided in these machines, but not shown, disengages the hoist clutch 42 and applies a brake by which the skip is temporarily held in its uppermost position, preliminary to being lowered by the control of the manual lever 43 which not only

actuates the clutch 42 but also controls the brake acting upon the hoist drum 45, so as to permit the skip to be gradually lowered to its batch receiving position. As the skip 1 was raised, its trip lever 8 actuated the arm 2a of the lever 2 and supplied water from the associated water tank and valve parts to the mixing drum 17. The mixing period for the drum 17 has now been started, and the skip is lowered by the operator as above described under the control of the lever 43. In its down movement, the skip operates the gear 18 to turn the latter in a clockwise direction, and thus cause the pawls 21 and ratchet wheel 21a to move the crank 23 exactly 180 degrees of its lower limit of movement. The crank 23 is connected, of course, to the deflector or gate 24 and thus the deflector 24 will swing from the position shown in full lines in Figure 2 to the dotted line position of Figure 2.

On the down movement of the skip, the lever 8 hits the valve lever arm 2b closing off the water supply to the drum 17 and opening the valve to supply water from the main supply to the tank 26. The skip is loaded again as before. After the drum has been mixing for a period of 25.5 seconds, a warning bell, of a known type in the art, such as shown by Lichtenberg Patent No. 1,770,176, issued July 8th, 1930 sounds, thus telling the operator that it is now time to again raise the skip in order to synchronize the operations for the rest of the day on which the machine is to work. (It will be understood that as thus far described, the machine is being set into operation so as to largely work automatically so far as synchronizing the action of the skip to the actions of the discharge chutes is concerned, the only manual operation that needs to be performed thereafter being the lowering of the skip by the operator of the machine, and also the operation of the boom 40 bucket 46 which travels out on the boom 47 to deliver the material to the site where it is to be laid.)

As stated above, the skip is now loaded, and is caused to be raised thereby turning on the water by the actuation by the lever 8 of the proper valve lever for the tank 25, the actuating rods 4, 30 and 31 being operated as the skip goes up, but without tripping the power discharge unit, as this cannot be done when the discharge chute is already in mixing position.

This lack of operation is due to the fact that the lever 4 is not in the path of movement of the arm 3. The trip lever 8 having now been turned to cooperate with the roller or abutment part 28 of the rod 29, hits this rod and pushes on the same so as to set the batchmeter 13. At the same time, the rod 12 is pulled thereby operating the coupler bar 15 disconnecting the same from the chute 7 and connecting it with the chute 6 rendering the latter operative by the power discharge. The skip is then lowered by the operator who handles the lever 43, this closing the valve for the water tank 25 and shifting the deflector 24 to the position shown by full lines again.

The skip is again loaded. The mixing period for the aggregates in the drum 17 has now lapsed. The batchmeter 14 releases by its automatic action well known, thus tripping the discharge unit 5, and this being at such time connected to the discharge chute 6, causes turning of the discharge chute 6 to discharge position. The power discharge unit simultaneously under these conditions commences automatically to control the skip and engages the skip hoist clutch through the rod 32, working on the lever 43, thus caus-

ing the loaded skip to be raised automatically from such time on, though of course, manual interference can be interposed at any time to such automatic upward movement of the skip if for some reason the operator of the machine 80 wishes again to take control.

The automatic operations described above are now repeated, and the skip is brought to the ground manually ready for a new charge. The mixing period in the drum 16 next lapses and the batchmeter 13 releases tripping the power discharge unit 5. The power discharge 5 being now connected to the chute 7, turns this chute to discharging position and automatically engages the skip hoist clutch through the push rod 32 aforesaid. From this time on the paver works fully automatic, with the exception of the lowering of the skip and the operation of the bucket 46 as previously stated, these two operations being manually controlled. The times of the various operations are synchronized by the batchmeters after being established by the operator, when raising the skip with the second batch.

The foregoing sets forth the preferred mode of arranging the mechanisms and providing for the automatic operations, but I wish it to be understood that my machine might be equipped if desired with one power discharge unit for each drum, instead of using the power discharge unit 5 as a common operating means for the discharges of both drums. Or again, it is within the purview of my invention to substitute a timing gear set into operation manually and thereafter possible of working automatically to control the opening and closing of the valves and the general timing of the action of the parts under which conditions, I would do away with the batchmeters.

A type of clutch knock-out and brake control means usable for the purposes of this invention 115 is shown in Lichtenberg Patent No. 1,328,635, issued January 20th, 1920.

Having thus described my invention, what I claim as new and desire to secure by Letters Patent of the United States, is:—

1. In a concrete paving machine, a plurality of concrete mixers, a charging instrumentality for said mixers movable from receiving to discharging position comprising a control member movable to cause the instrumentality to supply its contents to one mixer on each charging operation of the charging instrumentality, and then another mixer on the next operation of the charging instrumentality, mechanism to set the control member on each operation of the charging instrumentality automatically so that it will cause alternate charging of the mixers on successive operation of the charging instrumentality, discharge devices for the mixers, means interposed between the charging instrumentality and the said discharge devices to cause the discharge devices to alternately operate for the discharging of their respective mixers, means for synchronizing the action of the discharge devices with the action of the control member of the charging instrumentality, operating mechanism for moving the charging instrumentality to its charging position, mechanism to connect said operating mechanism with the charging instrumentality to move the latter to charging position, and means to synchronize the action of said operating mechanism with the actions of the discharging devices so that automatic action of the operating mechanism may be effected, and manual means whereby to manually initiate the action of the 150

operating mechanism preliminary to synchronization of the working of said operating mechanism with respect to the discharging devices.

2. In a concrete paving machine, in combination, a plurality of mixers, a charging device therefore arranged to perform mixer charging operations, a controlling instrumentality forming a part of the charging device to cause it to supply each mixer at a certain time separate from the time when the other mixer is supplied, discharge devices for the mixers including a power discharge unit, mechanism carried by the charging device for moving the controlling member thereof to proper positions for supplying the mixers at different times, and connecting parts for synchronizing the action of the controlling member of the charging instrumentality with the actions of the discharging devices so that the latter will be operated at different times to discharge the contents of their mixers, the connecting parts for the synchronizing purpose above mentioned including a power discharge unit, a coupler for coupling the power discharge unit to either one of the discharge devices of the mixers, and control connections between the controlling member aforesaid and said coupler substantially as set forth.

3. In a concrete paving machine, in combination, a plurality of concrete mixers, a charging skip for said mixers movable from receiving position to discharging position, a controlling member on the skip for deflecting the contents of the latter alternately into the mixers upon successive operations of the skip to charge the mixers, water supply means for the mixers to separately provide a measured quantity of water for each mixer, discharge devices for the mixers to separately discharge the same, and connections between the water supply means and said discharge devices leading to the controlling member of the charging skip so as to synchronize the actions of the discharge devices and the water supply means with the movement of the controlling member of the charging skip.

4. In a concrete paving machine, in combination, a plurality of concrete mixers, a charging skip for said mixers movable from receiving position to discharging position, a controlling member on the skip for deflecting the contents of the latter alternately into the mixers upon successive operations of the skip to charge the mixers, water supply means for the mixers to separately provide a measured quantity of water for each mixer, discharge devices for the mixers to separately discharge the same, connections between the water supply means and said discharge devices leading to the controlling member of the

charging skip so as to synchronize the actions of the discharge devices and the water supply means with the movement of the controlling member of the charging skip, and other means for controlling movements of the discharge devices of the mixers including parts operable by the skip in its charging action.

5. In a concrete paving machine, in combination, a plurality of mixing drums, a charging skip therefor movable from receiving to discharging position, comprising a controlling member movable to one position to cause supplying of the contents of the skip to one drum, and to another position to cause supplying of the contents of the skip to another drum, mechanism on the skip operable automatically incident to its movement to set the controlling member into the position stated by alternate movements of the controlling member, water supply means for each mixing drum, control connections between the controlling member of the skip and the water supply means to operate the water supply means for each drum alternately according to the position of the controlling member, batchmeter timing mechanism for each drum, connections between the batchmeter timing mechanism and the controlling member of the skip for alternate operation of said timing mechanism, discharge devices controlled by the timing mechanism of each drum alternately set into operation thereby and including a discharge power unit, manual means to control the movement of the skip after its discharging operations including a hoisting clutch, automatic means intermediate the power unit and said clutch for operating the clutch in synchronized relation to the operations of the discharge devices, and connections intermediate the power discharge unit and the skip independent of those previously referred to whereby certain operations of the discharge devices to assume non-discharging positions may be compelled in timed relations to the operations of the other parts of the machine.

6. In concrete mixing apparatus, a plurality of mixing drums, a charging skip common to said mixing drums and movable to and from receiving and discharging positions, a deflector coacting with said skip for deflecting the contents of the skip into one of said drums upon charging movement of the skip, and means for automatically adjusting the deflecting means in the lowering movement of the skip to a position for deflecting the contents of the skip into the other of said drums upon subsequent charging movement of the skip.

EMIL L. TRANAAS.
